(57) **CLAIM**

I claim the ornamental design for a straight saw scabbard, as shown and described.

DESCRIPTION

FIG. 1 is a front view of the straight saw scabbard according to the present invention;

FIG. 2 is a left side view of the straight saw scabbard according to the present invention;

FIG. 3 is a right side view of the straight saw scabbard according to the present invention;

FIG. 4 is a rear view of the straight saw scabbard according to the present invention;

FIG. 5 is a top view of the straight saw scabbard according to the present invention; and,

FIG. 6 is a bottom view of the straight saw scabbard according to the present invention.

The matter delineated in dashed lines forms no part of the claimed ornamental design.
